UNITED STATES PATENT OFFICE.

FRED W. GIARD, OF KENNEWICK, WASHINGTON.

BOX FORM AND STAND.

1,279,324.

Specification of Letters Patent. Patented Sept. 17, 1918.

Application filed April 29, 1918. Serial No. 231,486.

To all whom it may concern:

Be it known that I, FRED W. GIARD, a citizen of the United States, residing at Kennewick, in the county of Benton and 5 State of Washington, have invented new and useful Improvements in Box Forms and Stands, of which the following is a specification.

In the accompanying drawings:

- 10 Fig. 1 is a view in side elevation.
Fig. 2 is a view in end elevation.
Fig. 3 is a vertical section on line 3—3 of Fig. 1.
Fig. 4 is a top plan view.
15 Fig. 5 is a perspective view of certain rollers designed to bear against one of the end members of the box.
Fig. 6 is a section on the line 6—6 of Fig. 5.
20 Fig. 7 is a side elevation of the upper structure with the box in position, the latter having been turned into position for nailing one side thereof.
Fig. 8 is a section on the line 8—8 of Fig. 2.

This invention relates to a box form and stand, and the object is to provide certain novel construction including a stand proper, and means for holding the box elements in 30 position for nailing the bottom, and adapted for receiving various thicknesses of boards, and mechanism for shifting the position of the device for holding the box elements, in order that the nailing operation may be conducted on the opposite sides of the box.

With the foregoing and other objects in view the invention consists in the novel construction, combination, and arrangement of elements hereinafter described and claimed. 40 The stand proper comprises uprights 10 and 11 which are preferably formed of heavy material and are suitably braced by means of transverse members 12, 13, and 14, certain of these members having tongues or 45 tenons formed on the ends thereof and engaging recesses formed in members 10 and 11, the elements being suitably secured by nails or other engaging devices.

A plurality of vertically extending arms 50 15 and 16 are provided respectively with offsets 17 and 18, near the lower ends, these offset members having connection with a transverse rod 19 which in turn is connected with a pedal 20 mounted on a rock shaft 21. 55 Upper guiding devices 22 and 23 are pro-

vided upon the main portion of the stand and serve to guide the vertical bars, and lower guiding devices 23' and 24 are also provided, these devices last named being mounted opposite the offset portions. 60

Plate members 8 are carried by the upper ends of the elements 10 and 11 of the stand and serve to provide suitable supports for the box being formed when the latter has been shifted in position and at each stage 65 of the work.

An upper frame 30 includes a base plate 31 and side members 32 and 33 having pivoted connection with the arms 15 and 16 above mentioned. 70

Carried by plate 31 is a frame 35 comprising a base portion 36 mounted on cleats or the like 37 and 38', said plate or base last named carrying longitudinal side portions 38 and 39. A plurality of guiding devices 75 having oppositely located under-cut sides are designated 40 and 41, these devices being spaced apart, and guiding the longitudinal members 43 and 44 acting under the influence of a coiled spring 47. The longitudinally movable members are slotted at 47' and 48, and pins 49 and 50 extend through these slots and engage the base or the plate 36. Extending transversely through the longitudinal members are pins or axles on which 85 rollers 50', 51, 52, and 53 are mounted. The longitudinally movable members and the rollers carried thereby are spaced from the side members of the main frame and provide for boards or end pieces of different thicknesses. One side element of the box is held 90 between a plurality of tongues or resilient devices 55 and 56 upstanding from the base 31, a complementary member for retaining the side element of the box being designated 95 57 and being mounted on the frame carrying the longitudinally movable elements above specified. An additional upstanding device or devices 60 are mounted at the opposite side of the base 31 and serve to retain the 100 side element there located in position.

The upper structure mounted between the vertically movable bars 15, 16, may be shifted by hand after the said upper structure including the frame 30 has been elevated to 105 the required position by means of the pedal. Provision is thereby made for nailing the box on both sides thereof. Fig. 7 shows the box in position for nailing one of the sides thereof. 110

Tool holding devices 62 are carried by the uprights 10 and 11 in any convenient position.

In the use of the apparatus it is usually found convenient to employ the right hand in shifting the position of the box forming device and it is found that an operator can greatly increase his output as compared with hand work.

- 10 The several box elements are assembled as shown in Fig. 7, one side element being placed between resilient devices 55, 56 and 57, the ends of the box being placed respectively between the rollers and the members 32 and 33 constituting a portion of the rotatable upper structure. The other side of the box is then placed between upstanding resilient device 60 and the end members of the box, the several box elements mentioned 15 being then ready to receive the bottom board. The bottom is nailed to the side and end members of the box while the rotatable upper structure is in normal position, or in the position shown in Figs. 1, 2 and 3.
- 20 25 The bottom having been secured, the upper structure is rotated through an angle of forty-five degrees, that is to the position shown in Fig. 7, when one of the side members is nailed to the end members, and the upper structure and box are then rotated 30 through an angle of ninety degrees for the purpose of nailing the opposite side.

What is claimed is:

1. In a device of the class described, a

swingingly mounted frame, a stand, and 35 vertically movable bars for supporting said frame and elevating it above the stand, a plurality of projecting members carried by the frame, and positioned to retain the side elements of a box in position, means for retaining the end members of a box, said means last named including a plurality of longitudinal members movable in opposite directions, rollers carried by said members, said rollers being mounted in pairs and the rollers 40 of each pair engaging the end member in the box to be formed, and resilient means bearing against the longitudinal members.

2. In a device of the class described, a stand, a frame mounted above the stand, and 50 at times resting thereon, means for swingingly mounting the frame, means for effecting the upward movement of the frame, said frame including a base, and end members carried thereby, a second frame mounted on 55 the base of the frame first named, a plurality of longitudinally movable members mounted in the second frame, guides for directing the movement of said members, rollers carried by the longitudinally movable members, a spring 60 for spreading apart said members last named, and means carried by the frame first named and the second named frame for retaining in position the side members of a box while the bottom is being secured in position.

65 In testimony whereof I affix my signature.

FRED W. GIARD.
